UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON-ATTACHING MACHINE.

Original application filed February 26, 1925, Serial No. 11,664. Divided and this application filed June
23, 1925, Serial No. 39,070.

To all whom it may concern:

Be it known that I, FRANKLIN R. WHITE, a citizen of the United States of America, residing at Waterbury, in the county of New Haven and State of Connecticut, have invented certain new and useful Improvements in Button-Attaching Machines, of which the following is a specification.

My invention relates to new and useful 10 improvements in button attaching machines and more particularly to the means for receiving the button from the button chute and supporting the same as it is carried to the anvil to be attached by the action of the 15 plunger.

The present application is a division of an 20 application filed by me on February 26, 1925, bearing Serial Number 11,664, the above application being drawn to that part of the machine which feeds and delivers the tacks to the anvil.

The present application, also, is an improvement on the button receiving means as 25 shown in the patent granted to me on December 2, 1913, No. 1,079,968. As may be seen in that patent, in Fig. 9 especially, a pair of jaws is provided at the end of an arm, which jaws are cup-shaped at their outer ends and receive the buttons as they 30 pass from the button chute. These jaws lower with the plunger until the button is just above the cloth, after which the plunger forces the button still further downwardly, driving in the tack positioned on the anvil.

In years of actual service of the machine, as set forth in the Patent No. 1,079,968, I 35 have found at different times that the button after it leaves the escapement in the button chute, will pass down the chute into the button receiving member and due to its speed, the button will at times jump or fly from without the cup-shaped receiving jaws, so that when the plunger descends, the button head is missing.

In a patent granted to me on October 26, 1915, No. 1,157,743, there is shown an escapement for the buttons which is automatically 40 operated but which may also be manually operated, and in the past when a button jumped from the button receiving jaws the escapement was manually operated to thus feed another button to the cup-receiving jaws.

Desiring, therefore, to speed up the work

and to prevent the fed buttons from leaving 55 the cup-receiving jaws until attached, I have provided a similar set of cup-receiving jaws with the addition, however, of a superimposed set of jaws, so that when the button leaves the chute and slides within the main 60 button receiving jaws, the superimposed jaws will act as a top wall and prevent the buttons from jumping from without the main jaws.

Still another object of the invention is to 65 provide a button receiving means comprising two sets of pivotal jaws, the lower pair of which is cup-shaped at their outer end, to form a pocket for the buttons, while the superimposed pair are provided with lips 70 which extend over the cup-portion of the lower jaws, so that the button, although it may fly or jump slightly, cannot spring entirely without the cup-shaped pockets of the lower jaws.

Still another object of the invention is to 75 so construct the button receiving means that although a pair of superimposed jaws is provided to retain the button within the button receiving means, they in no way interfere with the stroke of the plunger as they are so constructed as to be spread and forced out of the way as the plunger starts its downward stroke.

Still another object of the invention is to 80 provide a button receiving means which may be quickly assembled, relatively cheap to manufacture and may be easily manually opened, if for any reason a defective button should be fed to the button receiving jaws.

With these and other objects in view, the 85 invention consists in certain new and novel constructions and combination of parts as will be hereinafter more fully described and pointed out in the drawings.

Referring now to the drawings showing a preferred embodiment of my invention,

Fig. 1 is a fragmentary side elevation of 90 a button attaching machine, the improved button receiving means being shown in their normal position.

Fig. 2 is a similar view showing the button receiving means being forced downwardly by the plunger to place the button directly above the tack.

Fig. 3 is a top plan view of the button receiving means showing the supplemental jaws in their normal position.

Fig. 4 is a detailed sectional view of the jaws and plunger in the position shown in Fig. 3.

Fig. 5 is a top plan view showing the supplemental jaws spread by the action of the plunger.

Fig. 6 is a detailed sectional view of the same.

Fig. 7 is a top plan showing both sets of jaws in their spread condition.

Fig. 8 is a detail section of the same.

Fig. 9 is a view of the button receiving member with the supplemental jaws removed, and

Fig. 10 is a view of the button receiving arm with both sets of jaws removed.

Referring now to Fig. 1, there is shown a fragmentary portion of a standard 1, provided with the bearing 2 for the reception 20 of the plunger 3 together with the button receiving arm 4. A fragmentary portion of a tucker slide 5 is shown as well as a portion of a means 6 for manually operating the same, all of which parts are fully described 25 in my co-pending application, bearing Serial No. 11,664.

An anvil 7 and the tack receiving jaws may be noticed at the base of the standard 1, but this portion of the device forms no 30 part of the present invention, this being shown in the patent granted to me on June 17, 1924, No. 1,497,818.

Still referring to Figs. 1 and 2, there may be seen a fragmentary portion of a button 35 delivery chute 9, which extends from a hopper (not shown) directly beneath the plunger 3, the position of the chute being such that the plunger may pass through the bifurcated end of the same.

The arm 4 is pivoted as at 10 within the standard and comprises the vertical part 11 from which extends the horizontal portion 12, and then the portion 13, in the form of an arm, extends downwardly towards the 45 plunger, as may be clearly seen in the several views.

Mounted on this portion 13 as may be seen from Fig. 10, is a small lifting member 14 pivotally held by the pin 15. The portion 13 of the arm is slotted at its end as at 16 and extending upwardly is the small spacer lug 17, while in alignment therewith and above the same, is the small post 18 with the integral cap 19 formed thereon.

Referring now preferably to Fig. 9, there will be noticed that pivotally mounted on the portion 13 are the split jaws 20, their inner ends being semi-circular as at 21 to encircle the post 18 and fit under the cap 19, these jaws being held shut by the provision of a small spring 22 which encircles the upper end of the jaws and has its ends fitting within the little apertures 23 in the jaw pieces as is the usual practice.

The outer ends of the jaws 20 are cupped

to form a pocket 24 for the buttons and the lips 24' form the bottom supporting walls of the pocket.

It might be mentioned at this point in the specification, that Figs. 3 to 9 inclusive, show the button receiving means and the plunger as well as the position of the several parts during the operation of the jaws when the plunger descends, and for the sake of clearness of illustration, the button has been 70 omitted from the pocket, but it will be appreciated that when the button is lodged within the main jaws, the plunger when assuming the position shown in Figs. 5 to 9 will impinge against the button head and the side walls or perimeter of the button will contact with the lower jaws to force them apart, rather than the end of the plunger.

The shape of these main jaws 20 and their construction is very similar to that shown in my Patent No. 1,079,968, small guide walls 25, however, are shown in the present form which are designed to guide the button as it leaves the chute 9 directly into the pocket at the end of the jaws. The jaws 20 are each provided with a threaded opening 26 for the reception of screws 27 which in turn are passed through the ends 28 of the two further jaw pieces 29 which are superimposed upon the jaws 20 as may be seen in the several figures.

Small holes 30 are provided in the sides of these jaws for the reception of the ends of the spring 31 which spring tends to keep these jaws normally closed as will be readily understood.

These jaws 29 are provided on their outer ends with the lips 29', the position and width of the jaws being such that the lips lie directly in the path of the plunger 3 as may be seen in the several figures. The right hand piece of the jaws 29 is curved slightly outwardly at its upper end, as may be seen in Figs. 3, 4 and 7, so that the same may be easily grasped by the operator if desired to open the jaws to remove any defective button.

The lips 29' of the jaws 29 lie directly above the pocket 24 or cup-shaped portion of the lower jaw and it will be readily understood that when a button passes down the chute 9, and drops into the cup-shaped portion and rests on the lips 29', of the lower jaws, it will be prevented from jarring or flying out of its pocket as the lips 29' form a substantial upper ledge or cover for the pocket.

Referring again for the moment to Figs. 1 and 2, as to the button receiving arm 4, it will be noticed that its upper and lower limits of movement are regulated by the upper set screw 32 and a similar lower one 33, the upper screw impinging against a portion 34 of the standard 1, and the lower one against a spring-pressed pin 35, the

spring (not shown) being encased within the housing 36.

The operation is as follows:—Presuming that a button has passed down the chute 9 and rests within the cup-shaped portion of the lower jaws 20, the plunger, in its regular cycle of operation will move downwardly and assume the position shown fragmentarily in Fig. 4. The lower end of the plunger presses against the slanting walls of the lips 29' of the jaws 29 and forces them apart as shown in Fig. 6. The plunger now impinges against the top of the button (not shown) and as the plunger descends it moves the arm 4 downwardly and forces the button against the lips 24' and spreads open these lower jaws, and the tack on the anvil will be forced through the material and up into the button head.

20 The lifting member 14 on the upward stroke of the plunger and the rise of the arm 4, will lift the button and cloth upwardly, after which the cloth will be pulled outwardly and moved for the next button.

25 It will be understood that as the plunger descends, the arm 4 and the jaws will move downwardly by the action of the plunger, this action being the same as in my previously mentioned patent. The advantages 30 of the present construction will be readily appreciated, as it is impossible for a button to speed down the chute into the lower jaws and fly therefrom as the supplemental jaws provide an upper wall, substantially closing 35 the cup-shaped pocket. The supplemental jaws in no way act as a detriment as the plunger easily spreads them as it contacts with their lips. The supplemental jaws are normally closed and are only opened when 40 the plunger spreads them.

From the foregoing it will be seen that I have provided a button receiving means comprising a main set of jaws, which are cupped at their outer end to receive the descending button and that I have provided a supplemental pair of jaws which are superimposed and restrict the button from any outward movement.

50 Many slight changes might be made without in any way departing from the spirit and scope of the invention.

Having thus described my invention, what I claim as new and desire to secure by Letters Patent is:—

55 1. In a button attaching machine, button feeding means, an arm, a pair of jaws mounted on said arm for the reception of a fed button, and a supplemental pair of jaws for retaining the button when fed within the first mentioned jaws.

60 2. In a button attaching machine, button feeding means, a pivotal arm, a pair of jaws mounted on said arm and cup-shaped at their outer extremities for the reception of

a fed button, and a supplemental pair of 65 jaws cooperating with said first mentioned jaws for preventing the button from flying upwardly when fed into the said first mentioned jaws.

3. In a button attaching machine, button feeding means, a pivotal arm, a pair of jaws mounted on said arm and provided with a pocket at their outer extremities for the reception of a fed button, and a supplemental pair of jaws superimposed upon said first 70 mentioned jaws and cooperating with said first mentioned jaws for preventing the button from flying upwardly when fed into the said pocket of the first mentioned jaws.

4. In a button attaching machine, button feeding means, a pivotal arm, a pair of spring-pressed jaws mounted on said arm and provided with a pocket at their outer extremities for the reception of a fed button, and a supplemental pair of 75 spring-pressed jaws cooperating with said first mentioned jaws for preventing the button from flying upwardly when fed into the said pocket of the first mentioned jaws.

5. In a button attaching machine, button feeding means, an arm, a pair of spring-pressed jaws mounted at the outer end of said arm and provided with a pocket at their outer extremities for the reception of a fed button, and a supplemental pair of spring-pressed jaws pivotally mounted on said first 80 mentioned jaws and normally forming a top wall above said pocket to prevent the button from flying upwardly from said pocket when the button is fed thereto.

6. In a button attaching machine, button feeding means, a pair of button receiving jaws, a pair of superimposed supplemental jaws cooperating with the first mentioned jaws and the said supplemental jaws comprising two pieces one of which is provided with a relatively short tooth and the other 85 with a relatively long tooth.

7. In a button attaching machine, a pair of button receiving jaws, and a pair of superimposed supplemental jaws cooperating with said first mentioned jaws, both of said sets of jaws being spring-pressed and one of the jaws of the upper set being struck on a greater arc than that of the other.

8. In a button attaching machine, button feeding means, an arm, a pair of spring-pressed jaws mounted at the outer end of said arm and provided with a pocket at their outer extremities for the reception of a fed button, and a pair of superimposed supplemental spring pressed jaws having two lips normally extending over the pocket in the first mentioned jaws to thereby prevent a button from flying upwardly from said pocket when a button is fed thereto.

9. In a button attaching machine, button feeding means, an arm, a pair of spring

pressed jaws mounted at the outer end of said arm and provided with a pocket at their outer extremities for the reception of a fed button, and a pair of superimposed supplemental spring pressed jaws having two lips normally extending over the pocket in the first mentioned jaws to thereby prevent a button from flying upwardly from said pocket when a button is fed thereto, and the said lips adapted to be forced apart by the action of the plunger.

10. In a button attaching machine, a standard, a plunger operable in said standard, a button chute extending directly beneath said plunger, an arm, a pair of spring-pressed jaws mounted at the outer end of said arm and provided with a pocket at their outer extremities for the reception of a fed button, said pocket extending directly in the line of the plunger, and supplemental jaws mounted on said first mentioned jaws to form a covering for said pocket and the said supplemental jaws being opened by the downward stroke of said plunger.

25. 11. In a button attaching machine, a standard, a plunger operable in said standard, a button chute extending directly beneath said plunger, an arm, a pair of spring-pressed jaws mounted at the outer end of said arm and provided with a pocket at their outer extremities for the reception of a fed button, said pocket extending directly in the line of the plunger, and supplemental jaws mounted on said first mentioned jaws to form a covering for said pocket, and the supplemental jaws, as well as the first men-

tioned jaws being spread apart by the downward stroke of the plunger.

12. In a button attaching machine, a standard, a plunger operable in said standard, a button chute extending directly beneath said plunger, a pivotal arm, a pair of spring-pressed jaws mounted at the outer end of said arm and provided with a pocket for the reception of a fed button, said pocket extending directly in the line of the plunger, and supplemental jaws mounted on said arm to cooperate with the first mentioned jaws to form a covering for said pocket, and the said arm, together with its jaws moving downwardly and the jaws spreading when said plunger is thrust downwardly.

13. In a button attaching machine, a standard, a plunger operable in said standard, a button chute extending directly beneath said plunger, a pivotal arm, a pair of spring-pressed jaws mounted at the outer end of said arm and provided with a pocket at its outer extremities for the reception of a fed button, said pocket extending directly in the line of movement of the plunger, and superimposed jaws provided with lips extending within the line of the plunger and said lips normally forming a cover for said pocket and the downward stroke of the plunger forcing the lips outwardly to allow the plunger to force the arm and jaws downwardly to thereby properly position the button for attachment.

In testimony whereof I affix my signature.

FRANKLIN R. WHITE.
